United States Patent Office.

HENRY S. LOPER, OF NEW HAVEN, CONNECTICUT, ASSIGNOR TO HIMSELF
AND HENRY S. PARSONS, OF SAME PLACE.

Letters Patent No. 96,452, dated November 2, 1869.

IMPROVED SHOE FOR CRIPPLES.

The Schedule referred to in these Letters Patent and making part of the same.

To all whom it may concern:

Be it known that I, HENRY S. LOPER, of New Haven, in the county of New Haven, and State of Connecticut, have invented a new Improvement in Cork Soles for Boots and Shoes; and I do hereby declare the following, when taken in connection with the accompanying drawings, and the letters of reference marked thereon, to be a full, clear, and exact description of the same, and which said drawings constitute part of this specification, and represent in—

Figure 1, a perspective view, and in

Figure 2, a longitudinal central section.

This invention relates to an improvement in that class of soles which is used in the manufacture of boots and shoes for persons who require one sole to be thicker than the other, as where one limb is shorter than the other.

Heretofore, in this class of shoes, a great difficulty has been experienced in making a flexible sole, which would not soon break at the connection of the shank with the ball, therefore, many manufacturers make the sole the same thickness through the ball and shank, in which case there is no flexibility in the sole.

The object of my invention is to construct a cork sole, with an elastic shank, the elastic shank being the connection with the ball and heel.

In order to the clear understanding of my invention, I will proceed to describe the same, as illustrated in the accompanying drawings.

A is the ball, which is shaped from cork into the desired form, and of the thickness required to make up the difference in the length of the limbs.

B is the heel, of a height corresponding to the sole.

C is the shank, which I form from India rubber, fixing one end firmly to the heel, and the other into the cork, as seen in fig. 2, so that the heel and ball are firmly secured together by means of the shank C.

The sole thus constructed is applied to the shoe in the usual manner of cork soles, and covered with leather, to finish the shoe.

I do not wish to be understood as broadly claiming an India-rubber shank for boots and shoes, as such, I am aware, is not new; but

What I do claim as my invention, and desire to secure by Letters Patent, is—

A shoe for cripples, when constructed of a cork sole or ball, and connected with the heel by an elastic shank, C, substantially as specified.

HENRY S. LOPER.
